Primary Examiner — Elizabeth J Oswecki(74) *Attorney, Agent, or Firm* — Young & Thompson(57) **CLAIM**

The ornamental design for a semiconductor device, as shown and described.

DESCRIPTION

FIG. 1 is a front, top, right side perspective view of a semiconductor device showing our new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof;

FIG. 7 is a right side view thereof; and,

FIG. 8 is a cross sectional view taken along line 8-8 of FIG. 4. The broken lines shown in the drawings represent portions of the semiconductor device that form no part of the claimed design.

1 Claim, 6 Drawing Sheets(56)
